United States Patent Office

Des. 180,025
Patented Apr. 9, 1957

180,025

FAN BLADE

Harry R. Killam, Livonia, Mich., assignor, by mesne assignments, to American Radiator & Standard Sanitary Corporation, New York, N. Y., a corporation of Delaware

Application July 19, 1954, Serial No. 31,489

Term of patent 14 years

(Cl. D26—7)

FIG. 1

FIG. 4

Figure 1 is a perspective view of a fan blade embodying my new design;

Figure 2 is a front elevation of the fan blade shown in Figure 1;

Figure 3 is a rear elevation of the fan blade shown in Figure 1; and

Figure 4 is a perspective view thereof taken from a different position.

I claim:

The ornamental design for a fan blade, as shown.
